ALEXANDER WEIDE, OF CHICAGO, ILLINOIS.

Letters Patent No. 94,534, dated September 7, 1869.

IMPROVED BRIDGE-GATE.

The Schedule referred to in these Letters Patent and making part of the same.

To all whom it may concern:

Be it known that I, ALEXANDER WEIDE, of Chicago, in the county of Cook, and State of Illinois, have invented a new and useful Improvement in Bridge-Gates; and I do hereby declare and make known that the following is a full, clear, and exact description of the same, reference being had to the accompanying drawings, and the letters and figures marked thereon, which form part of this specification.

My said improvement is designed to be used at the ends of swinging bridges and the abutments of roadways thereupon, so that when the bridge is closed, the said gate or guard lies below the bridge, so as not to interfere with the passing of carriages or foot-passengers, and when the bridge is opened, said gate or guard rises up and forms a barrier across the entire roadway and walks, to prevent persons from falling accidentally into the water, the closing of the bridge causing said gate to descend out of the way, as hereinafter specified.

My said improvement consist in a novel mode of constructing and operating the said bridge-gate; and

To enable those skilled in the art to know how to make and use my invention, I will now describe the same with particularity, making reference in so doing to the aforesaid drawings, in which—

Figure 1 represents a side elevation of my invention.

Figure 2 is a plan or top view of the same.

Figure 3 is a front elevation of the gate, as seen in looking from the river toward the abutment of the roadway.

Figure 4 is a rear view of the same, showing the frame-work.

Figure 5 is a central vertical section, taken at the line x , in fig. 2.

Figure 6 shows a bottom view of the bridge, with the means for operating the gates.

Similar letters of reference in the several figures denote the same parts of my said improvement.

The bridge-gate is to be arranged on each side of the stream to be crossed, making two gates for each bridge; but as they are exactly similar, and similarly operated, I have shown but one of said gates and the contiguous end of the bridge in the drawings.

A represents the roadway where it abuts upon the end of the bridge B, which is supported upon a central pier, revolving upon its centre in the ordinary manner, when it is desired to open or close the same.

There is a space left between the abutment and the bridge wide enough for the gate C, as seen in fig. 1.

The said gate C has a vertical reciprocating movement, the top of the gate being on a level with the bridge and roadway when the bridge is closed, but rising up a suitable distance above the roadway when the bridge is opened, as hereinafter described.

The gate is composed of the upper and lower curved bars C C, connected by the vertical bars D, as seen in fig. 3.

F F are two suitable posts or guides, to which the gate is attached by loops c c, which surround said posts F, and thus the posts F serve to keep the gate in place, and at the same time permit said gate to move up and down as desired.

G represents braces secured to the top of said posts F, to which also the guard-rail is attached, said brace passing down through the frame-work supporting the gate, where it is secured by two nuts, whereby the brace can be made rigid and firm as desired.

To the said gate is attached a bar, E, sloping up from each end of the gate to the centre, as seen in fig. 3, said bar being provided with a channel or groove, marked a, as is shown in figs. 1, 3, and 5.

This angular grooved bar E, secured upon the gate, is the means by which the gate is lowered and elevated by the closing and opening of the bridge, as hereinafter described.

J represents a shaft, upon which two pulleys, K K, are fixed, over which chains L pass, one end of said chains being secured to weights, W W, and the other end to said pulleys, so that by means of the teeth m, on said pulleys, which engage with the racks n on the gate, the weights W W serve as a counterpoise to the gate, so that it can be raised or lowered easily and uniformly, and without sudden or irregular movements in its descent.

The shaft, and rack, and pinion above mentioned, also serve another purpose, which will be hereinafter explained.

For the purpose of locking the gate in place when it is raised up, a lever, I, is fulcrumed to the central vertical bar D of the gate, its upper end being provided with a point or catch, i, and its lower end being thrown outward by means of an arched or projecting spring, H, as seen in fig. 5.

Near the top of the abutment, as seen in said fig. 5, is a small hole or socket, x, made in a plate secured in the proper position, so that when the gate is moved up to its desired height, the point i on the lever I is thrown into said hole x by means of the spring H, thus securely locking the gate in place, and preventing its being pushed down until the bridge closes. When the gate is down, the said catch passes through a hole in the bar D, to which the lever I is attached, as seen in fig. 5.

Upon the ends of the bridge are secured metallic plates b, arranged low enough so that when the bridge closes it will press in upon the spring H, and the lower end of the lever I, and detach the catch i from the socket x, and permit the gate to be moved down as desired.

At the centre of each end of the bridge is a pin or projection, marked *d d*, said pins being the terminations of the rods *M*, seen in fig. 6, which are attached to a rock-shaft, *N*, so that a person by moving a lever, *o*, can withdraw the said projections *d* into the ends of the bridge when desired, but which remain permanently projecting when the notch in *P* is locked upon said lever *o*, to hold it immovable, said locking-device being seen in fig. 2.

Having described the construction of my said improvement, I will now describe its mode of operation.

When the bridge is closed, the top of the gate lies level with the bridge and the roadway, as seen in fig. 5, and the pins or projections *d d*, on the ends of the bridge, lie in the apex of the groove *a*, or highest part thereof, as seen in said fig. 5.

When the bridge begins to turn in either direction, it is obvious that the effect of moving the pins *d* horizontally in the downward inclined groove *a*, will be to raise up the gate to which the grooved bar *E* is attached.

This process of raising the gate continues until the pin *d* passes out at the end of the grooved bar *E*, the gate in the meantime having been elevated a distance equal to the vertical distance between horizontal lines drawn, one through the apex and one through the lower end of the grooved bar *E*.

Just as the pin *d* escapes from the groove *a*, the pin *i* on the lever *I* is thrown into the socket *x*, and securely locks the gate in place.

It will be observed that the pressure to raise the gate is applied upon side thereof, although it may be upon either side, and hence there would be a tendency for the other end of the gate to sag, and not move up easily or in a level position.

By the arrangement of the shaft *J*, pinions *m m*, and racks *n n*, one pinion and rack at each end of the gate, it is obvious that the above-named difficulty is obviated, as the movement revolves the shaft, and the pinion raises the opposite end with the same move-

ment and rapidity that the pin *d* raises the end to which it is applied.

When it is desired to close the bridge, as the ends swing in the plates *b*, press in the spring *H* and the lower end of the lever *I*, thus withdrawing the catch *i* from its socket just as the pin *d* enters the lower end of the groove *a* in the bar *E*, so that the closing of the bridge, bringing the pin *d* to the apex of the groove, moves the gate down to its original position.

The pins or projections are made so as to be withdrawn, so that in case the bridge should be required to be opened when the gate was frozen in, or should be otherwise out of order, the pins could be removed, so that the bridge could be turned without affecting the gate. Any other suitable means may be employed for making said pins *d* removable than the manner herein shown.

Having described the construction and operation of my improvement, I will specify what I claim and desire to secure by Letters Patent.

I claim—

1. The combination of the grooved angular bar *E*, with a vertically reciprocating gate *C D*, arranged and operating substantially as and for the purposes herein set forth.

2. In combination with said gate *C D* and angular grooved bar *E*, the shaft *J*, pinions *m m*, and racks *n n*, arranged to operate substantially in the manner and for the purposes set forth and shown.

3. In combination with the gate *C D*, the lever *I*, with its latch *i*, the spring *H*, and a suitable socket, *x*, for the purpose of securing the gate in position when elevated until the bridge closes, substantially in the manner and for the purposes specified.

4. Providing the ends of the bridge with removable pins or projections *d*, to operate the gate, as and for the purposes set forth.

Witnesses: ALEXANDER WEIDE.

W. E. MARKS,
E. BRUNS.
